United States Patent Office

Des. 179,388
Patented Dec. 11, 1956

179,388

VAPORIZER STAND

Max Katzman and Lawrence Katzman, New York, and Meyer Block, Port Washington, N. Y., assignors to Kaz Manufacturing Co., Inc., New York, N. Y., a corporation of New York

Application April 12, 1955, Serial No. 35,479

Term of patent 14 years

(Cl. D83—1)

Fig. 1 is a perspective view of our vaporizer stand;
Fig. 2 is a top view of our vaporizer stand;
Fig. 3 is a front view of our vaporizer stand; and
Fig. 4 is a right side view of our vaporizer stand.
The characteristic feature of our design for a vaporizer stand disclosed resides in the stand portion having the configuration shown.

We claim:

The ornamental design for a vaporizer stand, as shown and described.
